Design No. 13,815, dated March 27, 1883.

UNITED STATES PATENT OFFICE.

CHARLES F. RITCHEL, OF BRIDGEPORT, CONNECTICUT, ASSIGNOR TO THE UNEXCELLED FIREWORKS COMPANY, OF NEW YORK, N. Y.

DESIGN FOR A TOY PISTOL.

SPECIFICATION forming part of Design No. 13,815, dated March 27, 1883.

Application filed February 5, 1883. Term of patent 3½ years.

To all whom it may concern:

Be it known that I, CHARLES F. RITCHEL, a citizen of the United States, residing at Bridgeport, Fairfield county, Connecticut, have 5 invented and produced a new and original Design for Toy Pistols, of which the following is a specification.

My newly-invented design for toy pistols consists of the ornamental configuration of the 10 sides of the breech, barrel, and revolving cylinder, as hereinafter described, reference being made to the accompanying engraving, which is a side elevation of a pistol having the sides figured in the ornamental design which 15 I propose.

At the upper end of a tessellated figure, *a*, bounded by scalloped edges *b*, and having a rosette, *c*, in the center, I make a plain-surfaced dart-shaped point, *d*, projecting downward. Over this point *d* is a trefoil device, *e*, under an arch, *f*. The plain between arch *f* and rear end of the spring for the revolving cylinder *g* is figured with the diagonal bar, consisting of the central stem and leaf figures, *h*, bordered by plain bars *i* and dotted bars *j*. The angles of the said plain, separated by the said diagonal bar, are figures with the twigs *k*, and the said plain is bordered on the sides with the plain rib *l*. The opening for the cylinder *g* is bordered with the plain rib *m*, which has points *n* at the front side of said opening. The plain in which the said opening for the cylinder is formed is bordered at top and bottom with ribs *o*, having inwardly-projecting 35 points *p*, and a rosette, *q*, is figured in the upper front angle of said plain. The sides of the barrel have the central plain figure, *s*, and chain device *t*, extending each way therefrom to the ends, where the chains connect with the terminal figures *u*.

I claim—

1. The design for a toy pistol, consisting of the plain behind the opening in the breech for the revolving cylinder, separated from the point-figure *a* of the breech by the plain dart-shaped figure *d*, the point of which extends downward in the figure *a*. 45

2. The design for a toy pistol, consisting of the trefoil device *e* in the angle of the dart-point *d* and under the arch *f*. 50

3. The design for a toy pistol, consisting of the diagonal bar of central stem and leaf figures, *h*, plain borders *i*, and dotted borders *j* in the plain behind the opening for the revolving cylinder. 55

4. The design for a toy pistol, consisting of the twigs *k* in the angles of the plain behind the opening for the revolving cylinder.

5. The design for a toy pistol, consisting of the opening for the revolving cylinder bordered with the plain rib *m*, having points *n* at the front end of said opening. 60

6. The design for a toy pistol, consisting of the plain on which the opening for the revolving cylinder is formed, bordered at top and bottom with ribs *o*, having points *p*, and having the rosette *q* in the upper front angle of said plain. 65

7. The design for a toy pistol, consisting of the sides of the barrel having the central plain figure *s*, chain figures *t*, and terminals *u*. 70

In witness whereof I have hereunto signed my name in the presence of two subscribing witnesses.

CHARLES F. RITCHEL.
